UNITED STATES PATENT OFFICE.

STEPHEN P. McDONNELL AND PAUL A. VILLARS, OF DALLAS, TEXAS.

TIMER FOR INTERNAL-COMBUSTION ENGINES.

Application filed March 29, 1926. Serial No. 98,169.

This invention relates to improvements in timers for contacts in electrical circuits and has for its object to provide a device of this description which will positively make 5 and break the several contacts in proper timed relation, and so constructed that there will be no lost motion between the contact parts due to wear or the loose fitting thereof.

It is also an object of the invention to provide 10 a timer which will prevent arching at contact points and further to prevent burning and roughness, thereby eliminating the causes of "missing" at the contact points.

Further objects are to provide a timer 15 which will make a perfect contact at points by taking up loose fitting of parts, thereby making easy starting of engines.

The invention will be fully understood by reference to the following detailed description, 20 in connection with the accompanying drawings, and wherein—

Figure 1 is a front view of a timing device constructed in accordance with the invention.

Figure 2 is a side view of the spur gear 25 illustrated in Figure 1, and showing the gear mounted on the cam shaft of an internal combustion engine.

Figure 3 is a perspective view of a support 30 for mounting the spur gear.

Proceeding in accordance with the drawings and wherein numerals are employed to designate the various parts, 1 denotes the shell of the timer and within which is disposed 35 an annular internal gear 2 which forms an insulation medium. This annular gear 2 is stationary and is held in position by the small bolts and nuts 3 and 4, the bolts comprising a part of the contact element 40 for the electrical current, the nuts holding in place the electric wires 5 leading to the battery. On the inner end of the contacts or bolts 3 are toothed segments 6, the both of which are alined with the teeth of 45 the annular gear 2. These toothed segments it will be observed are also counter sunk in the annular gear and thus serve to lock the gear in place.

Referring to Figure 2 it will be seen that 50 the cam shaft 7 has a sleeve 8 and upon the latter is mounted a bracket 9. This bracket has an aperture through which a swivel 11 on the sleeve passes. This permits the bracket to swing free on rotation of the cam shaft. The bracket 9 carries a spur gear 12, the pin supporting which is carried in the

apertures 13. Forming a part of the bracket is a curved arm 14, and on the sleeve 8 is an eyed projection 15. Connected between the projection 15 and arm 14 is a spring 16 60 for the purpose of providing tension on the spur gear to keep the teeth of the spur gear at all times against the sides of the teeth of the internal annular gear to insure a good electrical contact.

In operation of the device, the rotation of the cam shaft 7 will cause the spur gear to be rotated around inside the annular gear 2. As the spur gear 12 comes in contact with the toothed segments or contacts 6 a spark is 70 produced in the cylinder of the engine. There will be very little wear on the device, and such as there is will be taken up by the spring 16, even though the spur gear teeth become worn to an extent that they might 75 mesh loosely. Further, this spring 16 is so placed that it keeps contact at all times between the sides of the teeth and not the bottom thereof, thereby eliminating wear of the teeth of the spur gear into the bottom 80 of the annular gear 2. It will also not lose contact at points where needed when used in a motor vehicle while traveling over rough ground or when the vehicle is "bounced" up and down.

It should be understood also that changes and modifications may be made in the device in keeping with the appended claim.

What is claimed is:

A timer for internal combustion engines 90 in combination with the cam shaft thereof, comprising a shell with electrical contact members, an annular toothed rim member on the interior of the shell; the cam shaft of the engine projecting into the shell and having a 95 sleeve mounted on the shaft, said sleeve including a bracket for supporting a miniature shaft, a spur gear carried on the shaft and in mesh with the annular rim and contact points as the cam shaft rotates; said 100 bracket having formed thereon a curved arm, a spring connected to the arm, the opposite end of the spring connected to said sleeve; said spring for the purpose of holding the spur gear in close contact with the 105 sides of the teeth on said annular rim member and the contacts.

In testimony whereof we affix our signatures.

STEPHEN P. McDONNELL.
PAUL A. VILLARS.
